Primary Examiner — Austin Murphy(74) *Attorney, Agent, or Firm* — Holtz, Holtz & Volek PC(57) **CLAIM**

The ornamental design for an electric driver tool, as shown and described.

DESCRIPTION

FIG. 1 is a top, front, right side perspective view of an electric driver tool showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings are shown for illustrative purposes only and form no part of the claimed design.
